UNITED STATES PATENT OFFICE.

ARTHUR C. JEWETT, OF NEW HAVEN, CONNECTICUT, ASSIGNOR TO WINCHESTER REPEATING ARMS CO., OF NEW HAVEN, CONNECTICUT, A CORPORATION.

SHOT-SHELL.

1,305,113.

Specification of Letters Patent. Patented May 27, 1919.

Application filed November 29, 1918. Serial No. 264,486.

To all whom it may concern:

Be it known that I, ARTHUR C. JEWETT, a citizen of the United States, residing at New Haven, in the county of New Haven and 5 State of Connecticut, have invented a new and useful Improvement in Shot-Shells; and I do hereby declare the following, when taken in connection with the accompanying drawings and the characters of reference 10 marked thereon, to be a full, clear, and exact description of the same, and which said drawings constitute part of this application, and represent, in—

Figure 1 a view in longitudinal central 15 section of a flight-marking shot-shell embodying my invention.

Fig. 2 an enlarged sectional view of the flight-marking pellet or body.

My invention relates to an improvement 20 in shot shells designed with particular reference to being used in trap-shooting but not limited to such use, the object being to mark the path of the charge of shot for the guidance of the shooter.

25 With these ends in view, my invention consists in a shot shell characterized by having installed within it a flight-marking pellet or body consisting of a metal core surrounded by an ignitable composition and 30 adapted in weight to accompany the charge of shot and mark the path thereof.

My invention further consists in the construction hereinafter described and pointed out in the claim.

35 In carrying out my invention as herein shown, I employ a flight-marking pellet or body consisting of a metal ball 2 embedded in a spherical envelop of suitable ignitable composition 3, such, for instance, as magnesia 40 sium and barium peroxid. The metal core 2 may assume any convenient form, its function being to lend sufficient weight to the pellet to insure its accompanying the charge of shot and so indicate the path thereof. As 45 shown, the pellet is installed within an open-

ing 4 in the center of the rearmost wad 5 of the felt-driving wads 5, 6 and 7. Fire is communicated from the powder-charge 8 to the pellet through a central perforation 9 in the undershot cardboard wad 10. The 50 charge of shot 11 is confined between the foremost driving-wad 7 and the over-shot cardboard wad 12 which is held in place by forming a crimp 13 in the outer end of the tube or case 14. The shell also comprises a 55 base wad 15, a metal head 16 and a primer 17. When the powder-charge 8 is exploded by the primer 17, a tongue of flame passes through the opening 9 in the wad 10 and ignites the composition 3 of the flight-marking pellet which as the wads drop away, 60 accompanies the charge of shot, and continuing to burn, marks their flight, whereby the user of the arm is able to follow the course of the shot.

65 I claim:

A shot shell having a paper body, a shot charge and a powder charge located therein, a group of driving wads interposed between the said powder charge and shot charge, an 70 under shot wad interposed between the powder charge and the rearmost of the said driving wads and formed with a flame-transmitting opening, and a flight-marking pellet consisting of a core embedded in an envelop 75 of ignitable material, installed in the rearmost of the said driving wads in position to have flame communicated to it from the powder charge through the under shot wad, the said pellet being separable from the 80 wads and of sufficient carry to follow the charge of shot.

In testimony whereof I have signed this specification in the presence of two subscribing witnesses.

ARTHUR C. JEWETT.

Witnesses:

ERIK S. PALMER,
ARTHUR W. EARLE.
